US00D942572S

(12) **United States Design Patent** (10) **Patent No.:** **US D942,572 S**
(45) **Date of Patent:** **** Feb. 1, 2022**

(54) **POWERED WHEELED BOARD**(71) Applicant: **RAZOR USA LLC**, Cerritos, CA (US)(72) Inventor: **Joey Chih-Wei Huang**, Temple City, CA (US)(73) Assignee: **Razor USA LLC**, Cerritos, CA (US)(***) Term: **15 Years**(21) Appl. No.: **29/770,817**(22) Filed: **Feb. 17, 2021****Related U.S. Application Data**

(63) Continuation of application No. 29/717,684, filed on Dec. 18, 2019, now Pat. No. Des. 911,476, which is a continuation of application No. 29/664,559, filed on Sep. 26, 2018, now Pat. No. Des. 871,532, which is a continuation of application No. 29/633,000, filed on Jan. 11, 2018, now Pat. No. Des. 829,838, which is a continuation of application No. 29/576,467, filed on Sep. 2, 2016, now abandoned.

Primary Examiner — Cynthia M. Chin*(74) Attorney, Agent, or Firm* — Knobbe, Martens, Olson & Bear, LLP(57) **CLAIM**

The ornamental design for a powered wheeled board, as shown and described.

DESCRIPTION

FIG. 1 is a top, rear, left-side perspective view showing a powered wheeled board of my design;

FIG. 2 is a bottom, rear, left-side perspective view thereof;

FIG. 3 is a top view thereof;

FIG. 4 is a bottom view thereof;

FIG. 5 is a left-side view thereof;

FIG. 6 is a right-side view thereof;

FIG. 7 is a front view thereof; and,

FIG. 8 is a rear view thereof.

The broken lines illustrate portions of the powered wheeled board that form no part of the claimed design.

1 Claim, 6 Drawing Sheets# US D942,572 S
